INTERFERENCE REDUCING APPARATUS
FOR RADIORECEIVERS

John Albert Pixler, Benkelman, Nebr.

Application September 27, 1933, Serial No. 691,197

5 Claims. (Cl. 250—20)

This invention relates to apparatus for use in connection with radio receivers, one of the objects being to provide units of novel construction for use in connection with either or both the aerial and the ground and which act to reduce interference.

With the foregoing and other objects in view which will appear as the description proceeds, the invention consists of certain novel details of construction and combinations of parts herein-after more fully described and pointed out in the claims, it being understood that changes may be made in the construction and arrangement of parts without departing from the spirit of the invention as claimed.

In the accompanying drawings the preferred form of the invention has been shown.

In said drawings:

Figure 1 is a diagram showing the present apparatus connected to a radio receiver and providing an artificial ground.

Figure 2 is a similar view showing the apparatus used in connection with the usual ground.

Figure 3 is a similar view of a modified form of ground and aerial connection.

Figure 4 is an enlarged section through the serial and ground apparatus shown in Figure 1.

Figure 5 is a diagrammatic view thereof.

Figure 6 is a section through one of the induction coils.

Referring to the figures by characters of reference 1 designates a casing preferably divided into separate compartments by partitions 2. Each of these compartments is designed to hold snugly one of the several units constituting the present invention. In the structure illustrated in Figures 1, 2, 4 and 5 both aerial and ground units are shown. The aerial units have been indicated at A and B while the ground units have been indicated at C, D, E, F and G.

The aerial unit A comprises a tube 3 formed of carbon and seated in the ends of the opening 4 in the tube are centering rings 5 formed of a material constituting a conductor of electricity.

A core 6 is centered in one of these rings 5 and electrically connected thereto while another core 7 is centered in and electrically connected to the other ring 5. A spool 8 of steel is mounted on core 6 and is provided with a short coil of bare wire, indicated at 9, this coil being covered with a layer of insulation 10. Another coil 11 of insulated wire is wrapped about the spool 8 and the insulation 10, this large coil of insulated wire being electrically connected as at 12 to the core 6. Thus the coil 9 will receive an induced cur-

rent from the coil 11 and will conduct it to looped insulated wires 13 which are twisted about each other and are supported within but out of contact with the carbon tube 3. These loops are carried by and insulated from disks 14 supported by an insulated spindle 15.

The other end of the looped wires 13 is electrically connected to the insulated coil 11 on a second spool, a portion of this coil being extended around and insulated from a coil 9 of bare wire adapted to receive an induced current and transmit it to the core 7. The coils mounted on the two cores 6 and 7 are duplicates and both are illustrated by the disclosure in Figure 6.

In the unit A a magnetic force is set up between the two cores 6 and 7 and a portion of the energy received by core 6 will be shunted through the carbon tube A to the core 7. As shown in Figure 4 springs 16 can be interposed between the rings 5 and the cores 8 to hold the various parts properly assembled within the tube.

Unit B which can be used with or independently of unit A, includes a tube 17 of carbon and the ends of the opening therein can be closed by centering rings 18 carrying contact springs 19. 25 These rings serve to center terminal cores 20 and 21. Core 20 is electrically connected to one end of a looped wire 22 made up of twisted strands, the loops being supported by disks 23 mounted on a central stem 24 insulated from the core 20. 30 The other end of the looped wire is joined to an induction coil such as illustrated in Figure 6, the inner or bare wire 9 being joined to the wire 22 while the outer or insulated wire coil 11 is joined to the coil 11 of a reversely positioned similar induction coil. The inner or bare wire coil 9 of this latter device is joined electrically to a looped wire 25 formed of twisted strands carried by insulated disks 26 and the other end of the looped wire is electrically connected to the core 21. 35

The units A and B are for use in connection with the aerial X of the radio receiver Y and can be used either together or separately. If used separately, the lead 27 from the aerial X is extended to the terminal or core 20 while terminals 21 and 7 are coupled together as at 28. A lead 29 is then extended from the core or terminal 6 to the aerial post of the receiver Y. However should it be desired to use only one of these units, as for example unit A, the aerial lead 30 would be extended to the terminal or core 7 as shown in Figure 2, thereby cutting out unit B.

The units C, D, E, F and G constitute ground units. Unit C is adapted to be employed by itself 55

in connection with the usual ground, as shown in Figure 2 at which time a lead 31 would join one terminal of this unit to the ground post of the receiver while the other terminal of the unit 5 would be joined by a connector 32 to the earth. When the connection 32 is not used the other units D, E, F and G will be employed, these being connected as illustrated in Figures 4 and 5 as well as Figure 1.

10 The unit C consists of a carbon tube 33 having terminals 34 and 35 mounted in centering rings 36 containing springs 37 for maintaining electrical connections between these terminals and the tube. Stems 38 are alined with but insulated 15 from the terminals and each carries looped wires 39 which are twisted together. The two loops are electrically connected at one end as shown at 40 while their other ends are joined electrically to the respective terminals 34 and 35. These looped 20 wires are supported in the same manner as those heretofore described, they being carried by disks 41. The loops 38 are extended to the respective terminals 34 and 35, as shown.

25 The unit D consists of a coil preferably about five inches long and containing approximately seventy-two feet of insulated wire indicated at 42. The respective ends of the coiled wire are electrically connected to terminals 43 and 44.

30 The unit E is of the same construction as unit A, its terminals 45 and 46 corresponding with the terminals 6 and 7.

35 Unit F is of the same construction as unit D, its terminals 47 and 48 corresponding with the terminals 43 and 44.

40 Unit G is a carbon cylinder solid except for a small central bore 49 in which is mounted a rod 50 one end of which provides a terminal 51.

45 The units C to G inclusive are connected in series, there being an electrical connection 52 between the terminals 35 and 43, another connection 53 between the terminals 44 and 45, a third connection 54 between the terminals 46 and 47 and another connection 55 between the terminals 48 and 51.

50 When the apparatus is set up as illustrated in Figures 1, 4 and 5 the waves are received from the aerial X and enter the set by way of the units A and B. Instead of using the ordinary ground, an artificial ground is formed by the units C to G inclusive.

55 It has been found by actual tests that where parts are assembled as described there occurs a marked reduction in interference and a corresponding improvement in reception.

60 As before stated the units D to G inclusive might be dispensed with under some conditions as shown in Figure 2 and should the unit B, for example, also be dispensed with the set up would be the same as illustrated in Figure 3 wherein unit A (or, if preferred, unit B) is interposed between the aerial and the input of the set while

the unit C is interposed between the ground and the ground terminal of the set.

65 The apparatus constituting this invention can be made complete in itself for attachment to a receiving set or, if preferred, it can be built into the set. 5

What is claimed is:

1. Interference reducing apparatus for radio receivers including a carbon tube having spaced terminals for electrical connections with an aerial 10 and the input of the receiver respectively, looped wires within but out of contact with the tube, and induction coils connected to and arranged in series with the looped wires to provide an electrical connection between the terminals. 15

2. Interference reducing apparatus for radio receivers including a carbon tube having spaced terminals for electrical connections with an aerial and the input of the receiver respectively, looped 20 wires within but out of contact with the tube and induction coils connected to and arranged in series with the looped wires to provide an electrical connection between the terminals, each of said induction coils including a primary coil of bare wire and a secondary and larger coil of insulated 25 wire.

3. Interference reducing apparatus for radio receivers including a carbon tube having spaced terminals for electrical connections with an aerial and the input of the receiver respectively, looped 30 wires within but out of contact with the tube, and induction coils connected to and arranged in series with the looped wires to provide an electrical connection between the terminals, the ends of the tube being electrically connected to the respective terminals. 35

4. Interference reducing apparatus for radio receivers including a carbon tube having spaced terminals one of which is adapted to be connected to the aerial or ground terminal of a receiver, 40 looped wires within and spaced from the tube, and induction coils connected to and arranged in series with the looped wires to provide an electrical connection between the terminals, said tube also constituting an electrical connection between the terminals. 45

5. Interference reducing apparatus for radio receivers including a carbon tube having spaced terminals electrically connected thereto, looped wires connecting the terminals within the tube, 50 a second carbon tube having end terminals electrically connected thereto, looped wires between said terminals, induction coils connected in series with the looped wires and cooperating therewith to provide an electrical connection between the 55 terminals, a substantially solid carbon tube having a core of conductive metal, and coiled wires interposed between the carbon tubes, said tubes and coiled wires being connected in series, thereby to provide an artificial ground. 60

JOHN ALBERT PIXLER.
